UNITED STATES PATENT OFFICE.

J GROVE BROWN, OF GROTON, NEW YORK.

DUMPING-WAGON.

1,221,828.

Specification of Letters Patent. Patented Apr. 10, 1917.

Application filed September 26, 1914. Serial No. 863,739.

To all whom it may concern:

Be it known that I, J GROVE BROWN, a citizen of the United States, residing at Groton, in the county of Tompkins and State of New York, have invented certain new and useful Improvements in Dumping-Wagons, of which the following is a specification.

The purpose of this invention is to provide convenient means for tilting the bodies of endwise dumping vehicles and for holding the bodies in any desired positions of adjustment. The invention is particularly desirable in connection with chute wagons used for distributing broken stone in layers upon roadways, as illustrated, for instance, in my co-pending applications, Serial No. 796,436, and Serial No. 862,957, although useful also upon vehicles for other purposes. In chute wagons for the purpose stated, the material is transported to the point where the stone is to be laid, the body is then tilted rearwardly and the vehicle is moved forwardly while the material flows out through the chutes, and is laid in an even layer upon the roadway. As the vehicle carries usually a heavy load of stone, the center of mass of which shifts when the body is tilted, and as the angle to which the body must be tilted with respect to the frame, to cause the stone to flow, varies according to the grade of the roadway, it is necessary to provide safe and convenient means by which the operator can control the tilting movements of the body and hold the body in any position of adjustment.

These objects are attained by the present improvements, the details and operation of which will be clear from the following specification taken in connection with the accompanying drawing, in which,

Figure 1 is a side elevation of part of an endwise dumping vehicle, having my improvements applied thereto, the body being shown in normal position in full lines and in dumping position in dotted lines;

Fig. 2 is a detail view showing the brake for the windlass;

Fig. 3 is a front elevation of the hoisting and lowering mechanism and the locking and braking devices; and,

Fig. 4 is a detail view of one end of the upright to which the hoisting and lowering chains are attached.

Referring to the drawing, A indicates an endwise dumping vehicle, comprising a body

1 pivotally mounted at 2 in bearings supported from the vehicle frame 3. Upon the forward portion of the vehicle frame, at the rear of the driver's seat 4, are secured a pair 60 of standards 5, and in front of these are braces 6 extending from the standards down to the foot platform 7. A shaft 8 is mounted in suitable bearings in the upper ends of the standards 5, and upon this shaft is a 65 winding drum 9. A gear 10 upon the shaft of the winding drum meshes with a pinion 11 on a short shaft 12 supported by one of the standards 5 and by a short standard 5^a, the latter secured to cross-pieces 13 extending between the standards. A hand crank 14, upon the shaft 12, is provided for the purpose of operating the gears to turn the winding drum 9 in either direction. Two chains or cables, 15 and 16, are attached to 70 the drum near its opposite ends and arranged to wind and unwind oppositely thereon; that is, when the drum is turned, one chain will wind on to the drum while the other chain will unwind. One of these 75 chains, 15, has its free end connected to the upper end of a bowed upright 17, which is secured to the front endboard 18 of the wagon body and projects above and below the same, and the other chain, 16, has its 80 free end connected to the lower end of the upright 17. It will be evident that by turning the crank 14 in one direction, the chain 16 will pull upward on the upright 17 and raise the forward end of the wagon body, 85 while the chain 15, at the same time, will pay off or unwind from the drum 9, and will steady the upward movement of the body and prevent it from being tilted by the load; it will also be evident that when the hand 90 crank is turned in the opposite direction, the chain 15 will wind on to the drum and pull the forward end of the body downward, while the chain 16 will pay off and serve as a holdback to prevent the sudden dropping 95 of the body by reason of its own weight or the weight of the load. A brake drum 19 is secured to the shaft 12, and a brake band 20 surrounds this drum and is normally pressed against it by a spring 21 which surrounds 100 a pin 22, pivoted at 20^a to one end of the band and passing through a suitable opening in the opposite end 20^b of the band. This spring is interposed between the latter end 105 of the band and a bell crank lever 23 pivotally mounted on the band, the arrangement being such that the spring normally presses 110

the band firmly against the brake wheel to prevent rotation of the drum of the windlass. The bell crank lever 23 has one arm connected by a rod 24 to a lever 25 which is secured to a shaft 26 mounted in bearings 27 on the standards 5, and this lever is connected by a rod 24^a to a foot lever 28 suitably pivoted adjacent the footboard 7 in such position that the driver may readily place his foot upon the lever and thereby cause the spring pressed brake band to be released from the brake drum. A lever 29 is also attached to the shaft 26, and a locking bolt 30 is pivotally connected to this latter lever. 10 The locking bolt or latch bolt is adapted to engage a recess 31 in a plate or block 32, on the front of the wagon body, and a spring 33, surrounding the bolt, normally presses the latter to its locked position. 15 When the wagon body is in its normal position, the locking bolt engages the recess 31 and locks the wagon body against tilting movement. For transporting material the wagon body will remain normally locked. 20 Upon arriving at the point where the material is to be dumped and spread, the operator, without leaving the wagon, bears down upon the foot lever 28, and, through the medium of the rods 24^a and 24, the locking bolt and the brake band are simultaneously released, so that the windlass may be operated to cause the tilting of the body. As the wagon body is tilted to the dumping position, the two chains, connected and operating as described, steady the motion. When the body reaches the desired angle, the operator lifts his foot from the foot lever and the spring pressed brake band then grips the brake drum and prevents further turning of 30 the drum and tilting of the body. If it is desired at any time while the load is being delivered on the roadway, to change the angle of the body, the operator releases the brake by pressing upon the foot pedal and 35 then turns the windlass as much as is necessary to bring the body to the proper angle. The foot controlled brake is also a desirable feature in regulating the movement of the wagon body when the load therein tends to

race the windlass, as it enables the operator 50 to check or stop this racing. In bringing the body back from the tilted to the horizontal position, the operator holds the foot lever down until the body reaches the horizontal position, varying the pressure more 55 or less if a braking action is desired, and when the body reaches the horizontal position the foot lever is released and the body thereby becomes locked and the brake becomes set on the windlass. 60

The upright 17 is made in two parts, as shown, bowed oppositely for the sake of strengthening it laterally, and the chains are connected to threaded eye bolts 17^a (Fig. 4), mounted in cross-pieces 17^b between the arms 65 of the upright. By means of these threadded eye bolts, the slack in the chains may be taken up and adjustments made to compensate for wear. The upright 17 is arranged so that its ends swing in a plane centrally of 70 the winding drum, and as this upright is made comparatively long, and the chains are arranged to wind toward the center of the drum, the angle at which the chains pull upon the upright is very slight in any position of the wagon body, and this arrangement obviously lessens the labor of operating the windlass and avoids straining the parts. 75

What I claim is:

In an endwise dumping vehicle, a frame, a windlass supported upon the front end thereof, an endwise tilting body, an upright secured to the front of the body, oppositely winding chains or cables on the windlass 85 connected, respectively, to upper and lower parts of the upright, a lock for locking the body, in its lowered position, to the frame, a brake for the windlass, a manually operable lever, and connections between said lever 90 and said lock and brake for releasing the lock and brake.

In testimony whereof I have affixed my signature, in presence of two witnesses.

J GROVE BROWN.
